W. H. STEVENS

WALL CONSTRUCTION

Filed Aug. 26, 1920

Fig. 1.

Fig. 2.

Inventor:
William Henry Stevens
By Alpha Stevens Atty.

UNITED STATES PATENT OFFICE.

WILLIAM HENRY STEVENS, OF HAMILTON, NEW ZEALAND.

WALL CONSTRUCTION.

Application filed August 26, 1920. Serial No. 406,105.

To all whom it may concern:

Be it known that I, WILLIAM HENRY STEVENS, subject of the King of Great Britain, residing at Hamilton, in the Dominion of New Zealand, have invented a new and useful Improvement in Wall Construction; and I do hereby declare the following to be a full, clear, and exact description of the same.

10 My invention has been devised to provide for the erection of standardized dwellings, or other structures, by the combination of standardized pre-cast concrete members so formed as to allow of their ready assembly in the erection of the foundations, walls, floors and ceilings of the building.

The invention has more particular reference to walls made of slabs of pre-cast concrete and of standardized area and thickness, by means of which slabs walls of any desired height and length may be easily erected.

In the accompanying drawing, Fig. 1 is a face elevation and Fig. 2 a sectional end elevation of the wall slab according to my invention.

The wall slabs J as shown in the drawing are each made of standardized length and height and of suitable thickness.

30 The slab J is made in any approved manner to obtain the required rigidity and strength and may be re-inforced in any of the usual ways. The horizontal joints between the slabs are formed so that they overlap, as shown in Fig. 2, and thereby provide

a weathertight joint without the use of a binding composition. These overlapping edges are made so as to provide an outward inclination in the horizontal joint and also to leave a small air cavity J' (Figure 2) 40 between the lap in order thus to make the joint more effectively weathertight. When the wall is completed it may be surfaced in any of the usual methods.

In the erection of these walls they are 45 raised course by course, until the required height is reached, the several members interlocking with one another and making a firm solid wall.

I claim:—

50 A wall consisting of slabs, said slabs having along their horizontal edges continuous projecting portions, said portions being opposite the faces at the opposed sides of the block, and placed in overlapping relation 55 with adjacent slabs, the overlapping edges being inclined so as to provide outward inclinations in the horizontal joints, and also being less than half the thickness of the slab so as to leave small air cavities between 60 the laps, thereby producing an effective weather-tight joint.

In testimony whereof, I have signed this specification in the presence of two subscribing witnesses.

WILLIAM HENRY STEVENS.

Witnesses:

DAVID BROWN HUTTON,
JOHN MCKIMSON.
